OLNEY ARNOLD AND ISAAC LINDSLEY, OF NORTH PROVIDENCE, RHODE ISLAND, ASSIGNORS TO PAWTUCKET HAIR-CLOTH COMPANY.

Letters Patent No. 106,106, dated August 9, 1870.

IMPROVEMENT IN MACHINE FOR TRIMMING AND SHEARING HAIR-CLOTH, &c.

The Schedule referred to in these Letters Patent and making part of the same

To all whom it may concern:

Be it known that we, OLNEY ARNOLD and ISAAC LINDSLEY, both of North Providence, in the county of Providence and State of Rhode Island, have invented certain new and useful Improvements in Machinery for Trimming or Shaving Hair-Cloth and other fabrics; and we do hereby declare that the following is a full, clear, and exact description of the same, reference being had to the accompanying drawings making part of this specification, in which—

Figure 1 is a front elevation of a machine embodying our said improvements.

Figure 2 is an end elevation of the same.

Figure 3 is a front elevation of the trimming instrument detached, and shown in connection with the "table" B, hereinafter mentioned.

Figure 4 is a detached view of the deflector, hereinafter mentioned as forming part of the trimming instrument.

Similar letters indicate corresponding parts in all the figures.

Our invention relates to the employment of mechanism for removing the short broken ends of hair or similar weft that protrude from the surface of hair-cloth or other fabrics.

The first part of our invention relates to the apparatus for trimming off the ends or fibers that protrude from the surface of the web, and consists of a reciprocating cutting-blade, having its edge working close to the surface of the web, and in combination therewith of a deflector or holding-plate, between which the projecting fibers enter, and are held against the action of the cutter, which (by its motion) thus cuts them off close to the surface of the web, as will be more fully described; and

It also consists in the employment of two such cutting-blades or edges, and two such deflectors or holding plates, placed in a reverse order on the same stock, so that the said device will operate when moving in both directions; and

It also further consists in the employment of a series of said cutting instruments, working in connection with each other, so that the web may be trimmed across its entire surface, while a reciprocating motion may be given to the cutting instruments less than the breadth of the web.

The next part of our invention relates to the means employed to control the operation of the cutting apparatus, and consists in making the frame that carries the several cutting instruments movable, in such a manner that the instruments may be elevated readily from proximity to the fabric, and their action suspended, and again returned to the cutting position, to resume operation.

In the drawings—

F is the frame-work of the machine, at one end of

which is mounted, in suitable bearings, the delivery-roller A, upon which the fabric H to be trimmed or sheared is wound.

m is a table, consisting of a flat smooth surface, of some three or four inches in width, over which the fabric is tightly drawn by means of a tension-strap, h, on the end of the roller, and thence passes to the receiving-roller B, upon which it is wound with suitable rapidity to insure the proper presentation of the fabric to the cutting apparatus, by means of the spur-gear N, at the end of the roller, and the pinion T on the end of the shaft L, to which motion and power are communicated from the driving-shaft D, by means of a band running over pulleys on each.

A sliding rod, f, is provided with a fork at a, which straddles the shaft L, next to the pinion T, by means of which motion and power are communicated to either roller at pleasure, through the spur-gear S and pinion I, to revolve the roller A, and through the gear N and pinion T to revolve the roller B.

The trimming apparatus consists of a number of cutting instruments, E E E, secured at regular distances asunder on the sliding frame J, in a position to place the cutting instruments in line with and directly over the table m.

This sliding frame, with its instruments, has a reciprocating movement in guides b b formed in the upright frame-work G, by motion derived from the crank K through the connecting-rod c.

The position of the cutting instruments on the sliding frame J, and with reference to the fabric on the table m, is such that the two outside or extreme instruments will cut and trim toward and from each selvage or edge of the fabric, over a surface equal to the throw or stroke of the said crank, and that the intermediate instrument or instruments will be fixed at something less than the extent of the crank's movement from the others, in order that the swath or cutting range of each may overlap that of the adjoining one, and thereby insure a uniform trimming of the entire surface from selvage to selvage by a reciprocating movement less than the breadth of the web.

The cutting instruments are constructed as shown in fig. 3, with a two-edged blade, n, on a cutter-stock, E E, which is bolted to the front of the sliding frame J, as shown in fig. 1.

The said blades are made with two cutting-edges, i i, to make a cut with each stroke, forward and backward, of the crank, and to cut in either direction from the extremity of the protruding end of weft toward its point of protrusion or root, as, from the nature of the fabric, the broken ends of weft project in either direction from the warp threads, as shown in figs. 1 and 3, and if, by reason of the broken ends protruding in the same direction with the movement of one edge of the cutting instrument, the end is passed over,

and not cut by the return movement, this protruding end will be properly presented to be cut by the other opposite cutting-edge of the same blade.

In setting the cutter-stocks in the frame J, care should be taken that the cutting-blades of each of the two outside instruments, which cut from the selvage toward the middle of the web, move only up to the selvage, and not over or past it, as, in such case, by the return or cutting stroke, the cutter will surely cut or otherwise damage the web or fabric.

The cutting action of the blades is facilitated by the deflectors R, figs. 3 and 4, consisting of metal plates with serrated or toothed edges, *r r*, having an inclination in the opposite direction from the cutting-edge of the blade at which they are held by adjusting screws, *v v*, as shown. The serrated edge is placed just above the said cutting-edges, and with a slight space between the two parts, for the admission of the extremity of the broken weft, and the lower surface of the deflector is smoothly polished so that the end of the broken weft, on meeting the polished surface, will be depressed and carried into one of the notches of the deflector's edge, so that the moving blade will pass to the point from which the weft protrudes, and sever it close to the surface of the fabric. The notches of the serrated edge of the deflector support the protruding end of weft, and prevent it from springing aside and escaping from the cutting-edge of the blade in its rapid movements, and is of the first importance to the successful operation of the cutting apparatus.

In placing the fabric in the machine it is necessary to remove the cutting instruments from their proximity to the table *m*, so that the end of the fabric may be inserted beneath the instruments, and attached to the roller B. For this purpose the cutting apparatus is slightly elevated from the table, to accomplish which the frame-work G, in which the cutting apparatus slides, is pivoted at *g*, at each end, and the opposite side from which the cutting apparatus extends is swung upward by means of a rocker-shaft, with suitable arms extending in opposite directions therefrom, to one of which the rod O and the lever

P is connected, and the arms upon the opposite side of said shaft bear against the under side of the frame-work G, so that by carrying the free end of the lever P downward, the front side of the frame-work and the cutting apparatus is lifted from the table *m* out of the way. This arrangement of elevating the cutting apparatus at will also places the same under the complete control of the operator, and is of great service in suddenly arresting and suspending the action of the cutting apparatus, while the remainder of the machine continues in motion, to prevent injury to the fabric from any cause.

Having described our invention, What we claim, and desire to secure by Letters Patent, is—

1. The combination of a shaving-blade and a deflector, or its equivalent, for deflecting the protruding hair or fibers against the edge of the blade as the instrument moves over the surface of the fabric, substantially as described.

2. The combination of two cutting-edges and two deflectors, or their equivalents, placed in a reversed order in one stock, so that the device will operate while moving in both directions, substantially as described.

3. The employment of a gang or series of the said trimming or shaving instruments, in combination with a suitable bed or table over which the cloth or fabric is carried by suitable means, the whole being and operating substantially as shown and described.

4. The trimming instruments, substantially such as are described, combined with an oscillating frame and means for moving it, in order that the said instruments may be elevated or removed from the table, or its equivalent, for spreading and presenting the fabric, substantially as described.

In witness whereof we have hereunto set our hands this 20th day of May, A. D., 1867.

OLNEY ARNOLD.
ISAAC LINDSLEY.
